EXERCISING DEVICE

**Theodore H. Belling, Barrington, R. I., assignor to
Fram Corporation, a corporation of Rhode Island**

Application July 13, 1945, Serial No. 604,747

10 Claims. (Cl. 272—57)

1

This invention relates to an exercising device more particularly designed for exercising the leg of a human being.

It is found, in administering to a broken hip or upper part of the leg or the like, that exercising of the leg stimulates healing and recovery. The devices which have heretofore been provided for the exercising of the human body usually anticipate that the body is in good health and parts are normal and full use of the leg may be had.

One of the objects of this invention is to provide an exercising device for a person who has not complete use of the body, more particularly the leg, by reason of some injury.

Another object of this invention is to provide a device which may be used while a person is lying in bed.

Another object of this invention is to provide a device by which the amount of resistance to movement of the leg may be varied.

Another object of the invention is to provide a device which will move in accordance with the length of radius of the arc over which the leg is moved.

With these and other objects in view, the invention consists of certain novel features of construction, as will be more fully described and particularly pointed out in the appended claims.

Figure 1 is a perspective view illustrating the device as mounted upon a fragmental portion of a bed, and showing fragmentally a person's foot as positioned in the device.

Figure 2 is an elevation of the device alone.

Figure 3 is a top plan view of end portion of the track, with the carriage mounted thereon.

In proceeding with this invention, I provide a track, which may be mounted upon the bed and upon which track there is a carriage upon which the foot of the user may rest and which will support the foot above the bed so that the carriage may be moved along the track by manipulation of the leg of the user. An arrangement is provided whereby a greater or lesser resistance to movement of the leg is provided.

With reference to the drawing, 10 designates generally a bed having a foot board frame 11. The foot 12 of the user of the device is shown as extending from beneath a blanket or other covering 13.

The device of this invention comprises a base, designated generally 15, comprising a platform 16 having side flanges 17 on either side thereof which are slotted as at 18 along their end portions. Slideably mounted in each of the slots 18 are the ends 19 of a bar which extends across the

2

base 16 and into the slots 18 in the opposite flanges. A runway or track, consisting of sections 20 and 21, hinged at the center at 22, is attached to the bars 19 so that the sections of the track 5 may be raised from the base 16 a desired amount, and supported by a block 23, which is positioned beneath their junction at the hinge 22. By this arrangement the sections 20 and 21 may be raised a desired amount, to provide the angular inclination which may be found desirable and supported in this position by a block 23 of the desired height. For instance, a 2" x 3" block 23 might be rotated through 90° from the position shown in Figure 2, so that a different height of the block would be 10 effective.

A carriage designated generally 25, consists of a platform 26 having an upstanding U-shaped rest 27 with side walls 28 and 29, which may carry a cushion 30 within this U-shaped formation so 15 as to receive the leg 12. Wheels 30 and 31 are provided on one side of the platform 26 and wheels 32 and 33 are provided on the other side of the platform 26. These wheels are arranged on axles 34 and 35 which converge so that the carriage in 20 its normal movement along the surface of the track sections 20 and 21 will move on the arc of a circle whose radius is substantially the length of the leg, or the distance from the hip joint to the heel. As the leg is swung sideways to exercise the same, the carriage will take a movement back and forth on an arc so that it will not slide 25 out from beneath the foot as this movement occurs. The inclination will be selected so that some pressure is required to swing the leg up the incline of the section 21 from the position shown in Figure 1 or 2, and then the leg may move down the incline of the section 20.

In order to arrest the movement of the carriage at the ends of the track, I provided abutments 40 36 and 37 which are cushioned as at 38 along their inner surface, and these abutments also converge so that they will be at right angles to the arc of swing of the carriage as it engages either one of the abutments at the end of its travel. 45 Thus both wheels 32, 33 or 30, 31 will engage the abutment at the same time, and no tendency to shift the carriage from the arc over which it travels will occur.

In order that the leg 12 will not engage the 50 track when in a raised position, I cut back the near edge of the track along the arc 40 through a length sufficient to clear the leg as moved along the track.

I claim:

1. An exercising device comprising a carriage

shaped to receive the foot of the user and support the leg when lying prone, rolling means supporting said carriage and arranged to direct said carriage on the arc of a circle having a radius substantially the length of the leg.

2. An exercising device as set forth in claim 1 wherein said carriage is U-shape providing side walls against which the foot may press to roll the carriage.

3. An exercising device as set forth in claim 1 wherein said rolling means comprises wheels whose axles converge toward the user.

4. An exercising device as set forth in claim 1 wherein said rolling means comprises four wheels, two of which have the same rotative axis and said axes converge toward the user.

5. An exercising device as set forth in claim 1 wherein a track is provided over which said carriage moves.

6. An exercising device as set forth in claim 1 wherein a track is provided over which said carriage moves and said track is inclined to the

horizontal in the direction of travel of the carriage.

7. An exercising device as set forth in claim 1 wherein a track is provided over which said carriage moves and said track is inclined to the horizontal on either side of its mid point.

8. An exercising device as set forth in claim 1 wherein a track is provided over which said carriage moves and said track is inclined to the horizontal on either side of its mid point with the mid point the highest.

9. An exercising device as set forth in claim 1 wherein a track is provided over which said carriage moves with abutments provided at the ends of the track.

10. An exercising device as set forth in claim 1 wherein a track is provided over which said carriage moves with abutments provided at the ends of the track said abutments extending along a radius having substantially the arc of said circle over which said rolling means act.

THEODORE H. BELLING.
